238,131

COMBINED BED AND STORAGE UNIT

Michael A. Mendlin, Springfield, N.J., assignor to
Bunk Trunk Distributors, Paramus, N.J.

Original design application July 6, 1971, Ser. No. 160,237,
now Patent No. 227,724. Divided and this application
Apr. 16, 1973, Ser. No. 351,633

Term of patent 14 years

Int. Cl. D6—01

U.S. Cl. D6—80

FIG. 1

FIG. 2

FIG. 3

FIG. 4

FIG. 5

FIG. 6

FIG. 7

FIG. 1 is a front, top and right side perspective view of a combined bed and storage unit showing my new design with the trundle bed in a partially opened position and the front door in the right storage column in opened position;

FIG. 2 is a front elevational view with the trundle bed and door shown opened in FIG. 1 in closed position;

FIG. 3 is a right side elevational view thereof;

FIG. 4 is a rear elevational view;

FIG. 5 is a left side elevational view of the bed in the condition of FIG. 2;

FIG. 6 is a top plan view thereof; and

FIG. 7 is a bottom plan view thereof;

This is a division of design application Ser. No. 160,237, filed July 6, 1971, now Pat. No. D. 227,724.

I claim:

The ornamental design for a combined bed and storage unit, substantially as shown and described.
